his ATTORNEY.

UNITED STATES PATENT OFFICE

SHERMAN B. WALKER, OF NEWTON, NEW JERSEY, ASSIGNOR OF TWO-FIFTHS TO BESSIE MABIE, OF MONROE, NEW JERSEY

PICKER STICK CONNECTION FOR LOOMS

Application filed November 3, 1931. Serial No. 572,842.

The present invention relates to a clamping device for picker stick staffs. Heretofore it has been customary to drill holes in the picker stick, usually made of hard wood, in order to securely clamp the means for supporting the sweep stick and its accompanying lug strap. The lug strap is usually made of leather or similar flexible material.

As is well known in the art, the sweep stick 10 co-acts with the lay of the loom and therefore it is thought that an extended explanation of this feature is not necessary. Drilling holes through the picker stick has a tendency to considerably weaken the same and a breakage 15 of the stick obviously results in serious damage to the loom. With this in mind, I have constructed an adjustable pillow for the lug strap and its sweep stick without resorting to any drilling of the picker stick staff. Ex- 20 perience has proved that this is a superior construction, resulting in more accurate adjustments for the height of operation of the lug strap and the prolonged life of the picker stick staff.

25 I also provide means carried by the adjustable pillow blocks to confine thereon the lug strap without however causing any binding action therebetween. This feature is also thought to be important since the lug straps 30 vary in their dimensions particularly in their height.

A practical embodiment of the invention is represented in the accompanying drawing forming a part of this specification, in which 35 similar characters of reference indicate corresponding parts in all the views.

Figure 1 is a side elevation of a picker stick provided with my improvement.

Fig. 2 is a horizontal sectional view of an 40 enlarged scale, on line 2—2 of Fig. 1.

Fig. 3 is a vertical sectional view on line 3—3 of Fig. 1; and,

Fig. 4 is a vertical sectional view on line 4—4 of Fig. 1.

45 In the accompanying drawing, numeral 1 denotes the picker stick staff pivoted at 2. At 3 is shown a flexible strap which is connected to the usual actuating spring 4 for returning the picker stick to its initial position.

50 I have shown at 5 an appropriate sweep

stick and the usual lug strap 6. The numeral 7 denotes a pair of hard wood pillows adapted to be slidably, yet rigidly mounted, on the opposite faces of the picker stick staff. To readily accomplish this there is shown on 55 each of the pillows 7 an encircling metal strip 8. Substantially mid-way between the longitudinal faces, these metal strips are serrated as shown at 9. Screws 10 are provided to positively fasten these strips to the aforementioned metal strips. As will be seen, the 60 serrations of the metal strips 8 will embed themselves into the opposite faces of the picker stick staff and rigidly hold the wooden pillows, supporting the lug strap in position. The extreme ends of the metal strips 8 are 65 provided with a right angular bend 11 and 12. These ends are apertured for the reception of a bolt 13 provided with an adjusting thumb nut 14. It will be readily seen that 70 these metal strips reinforce the wooden pillows and prevent a splitting or cracking thereof when the thumb nuts are tightened. At 15 is shown another bolt provided with an 75 appropriate conventional thumb nut 16. The square part of the round shank is designated at 17 with the head of the bolt 18.

A U-shaped member 19 has its upper extremities slotted as at 23 and are disposed in superimposed relation to each other as shown 80 at 20. Rivets 24 extend through the superimposed ends of the shanks 19 and carry a cushion 21 for engagement with the upper edge of the lug strap. By virtue of this construction it will be readily seen that the U- 85 shaped element automatically conforms itself to the distance between the two pillows 7.

The lower ends of the parallel extending shanks of the U-shaped member are preferably provided with a plurality of equi-dis- 90 tant spaced square holes 22 to accommodate the bolt 15 and prevent the turning of the U-shaped member with respect to the aforementioned pillows. By virtue of this construction, I have readily provided means to adjust the U-shaped element to any height of the lug strap that may be encountered on different types of looms. The front part of the supporting pillows is preferably notched as 95 at 25, to prevent possible cutting into the 100

blocks, caused by the metal parts of the sweep stick and the rear part is preferably rocker-shaped as at 26 to give the lug strap more play, when the picker staff goes forward.

5 Thus it will be seen that I have provided a simple and inexpensive means for adjustably supporting the sweep stick and its accompanying lug strap. I have accomplished this without drilling holes in the picker stick staff or weakening the same through recesses or other means. Hence the operator is enabled to readily adjust the lug strap precisely at any desired height. All that the operator has to do is to slide the pillows along 10 the face of the picker stick staff and after they are located at a desired height a tightening of the thumb nuts 14 and 16 will rigidly secure the same, the serrations 9 of the metal strips 8 will then bite in the opposite faces of 15 the picker stick staff.

Changes may be made in the details of the construction and the arrangement of the various parts of my device without departing from the real spirit and purpose of my invention, and it is my intention to cover by my 25 claim any modified form of structure or use of mechanical equivalent, which may be reasonably included within their scope.

Having thus described my invention, what 30 I claim and desire to secure by Letters Patent is:

A picker stick clamping device comprising a pair of parallel arranged supporting pillows, said supporting pillows being provided 35 with metal bands, said metal bands being serrated for a distance substantially corresponding to the width of the picker stick staff, a pair of adjusting bolts being carried by the wooden blocks and provided with adjusting thumb nuts, and a U-shaped element, 40 adjustably carried by the pair of supporting pillows, the shanks of which extend in a vertical position to said pillows and their extreme upper ends being superimposed and 45 slotted for lateral adjustment, a lug strap cushion carried by said superimposed members and rivets carried jointly by them, adapted to hold this aggregate in substantially parallel relation and permit slight 50 lateral adjustment thereof.

SHERMAN B. WALKER.
